LEROY R. GRUMMAN, OF PORT WASHINGTON, LONG ISLAND, NEW YORK

FLYING-BOAT AND LIKE CRAFT

Application filed July 13, 1929. Serial No. 377,942.

This invention relates to air and water craft, that is to say to flying-boats, amphibians, seaplanes and the like. Craft of this character, when of the tractor type, are inconvenient for passengers and crew entering or leaving the plane, and are difficult to bring up to docks and moorings. When the plane is on the water and is approaching a landing place it is desirable for a man to go forward with a rope to make the plane fast to the mooring, but this necessitates stopping the engine in order that he may get past the propeller in safety, and if the propeller is started again while he is on the forward deck he is exposed to considerable danger. With the propeller stopped the plane drifts with the wind, and it is consequently a matter of considerable difficulty and wasteful of time to get the craft up to the landing place. In order to gain the forward deck it is usually necessary for a person to get out of the back of the cockpit or cabin and go forward over the wing, which is awkward.

The object of the present invention is to provide a safe and convenient way for persons to enter and leave the craft while the propeller is turning, and to enable a member of the crew, or the pilot himself if he is alone, to reach the forward portion of the float or boat without the necessity of stopping the propeller. To this end the float is designed to afford an enclosed passageway beneath the propeller, and a front entrance is provided ahead of the tractor propeller. In connection with this entrance a movable shield is provided to keep passengers and crew from getting into the propeller. Specifically, the hatch cover is made to open in such a way that it forms an effective guard for this purpose, the cover therefore serving a double purpose.

In the accompanying drawings forming part hereof:

Fig. 1 is a perspective view of a flying-boat or amphibian plane provided with the invention, the hatch cover being shown in the open, propeller-guarding position;

Fig. 2 is a side elevation on a larger scale of the forward half, more or less, of the boat

body, showing a fragment of the propeller behind the raised hatch cover;

Fig. 3 is a vertical longitudinal section through the portion of the forward deck containing the hatch or entrance, the cover being shown partly raised in full lines, the fully raised and locked position being indicated by broken lines;

Fig. 4 is a similar view, showing the cover closed; and

Fig. 5 is a vertical transverse section taken on the line 5—5 of Fig. 4.

The airplane illustrated in these drawings has a central flotation body 2 containing the places for the pilot and passengers or crew. One of the seats in the interior is indicated at 3 in Fig. 2. The wings of the plane are marked 4, and 5 is a forward propeller driven by an engine 6.

The boat or float 2 is of a familiar form having a decked-over nose portion 7 which lies close beneath the propeller circle and extends forward of the propeller for a considerable distance. The deck of this portion is marked 8.

In this deck, directly in front of the propeller, I provide a hatch opening 9, large enough for a person to go through, and I arrange that the interior of the body shall afford a passageway from this entrance to the part of the body occupied by the pilot and others. It will therefore be understood that the interior is substantially unobstructed from the bulkhead 10 at the front of the hatch rearward to the pilot's and passengers' places. A step 11 at the foot of the bulkhead and directly below the forward part of the hatch makes it easy to get in and out of the opening.

A cover 12 ordinarily closes the hatch opening, and in this position lies substantially even with the deck 8. This cover is hinged to the deck at its rear end, so that when the cover is raised to permit entrance and egress it stands at an inclination directly in front of the lower portion of the propeller circle in such manner as to prevent persons using the front entrance or standing on the forward deck from getting foul of the propeller.

Means are provided for locking the hatch-

cover propeller-guard in this position, and also for locking it closed. The particular mechanism may be widely varied, but I preferably employ a toggle arrangement consisting of a pair of links 13 pivoted at 14 to the under side of the cover, and a pair of links 15 pivoted at 16 to brackets 17 secured to the under side of the deck at the sides of the hatch opening, the links 13 and 15 being pivotally connected to each other at 18. The links 15 may be of angular section so that when the cover is fully raised and the links are carried slightly past center by a spring 19 the portions of the links adjoining the pivots 18 will abut to form a stop preventing further flexing of the toggles in this direction. The weight of the cover and the action of the spring lock the toggles in this condition, holding the cover securely in the guarding position; and it is necessary to "break" the toggles before the cover can be lowered.

In the closed position of the cover the toggles are folded, and the spring holds them stopped against each other in a position with the line of centers 14, 18 back of the center 16, so that the links 15 act as rigid struts to prevent the cover rising under the action of the wind or otherwise. In order to raise the cover it is necessary first to swing the links forward from this locking position. It will be understood that there is sufficient looseness in the pivots or sufficient yielding in the links to permit of this being done. It adds to the security that some force is required to swing the linkage forward from the position of Fig. 4.

The pivot 14 may be a transverse shaft connecting the two links 13 and journaled in bearing brackets 20 on the cover. Operating knobs 21 may be fixed to the inner ends of the pivots 18.

From the foregoing it will be perceived that my invention makes it feasible and safe for crew and passengers to enter or leave the plane from the front, while the propeller is turning, also that it is made safe and easy for a member of the crew to take up a position forward of the propeller while the craft is proceeding under control on the water.

As has already been indicated, this is of very great advantage in coming up to a dock or mooring. At such times it will be convenient for the man to stand in the entrance, preferably on the step 11, a position in which there is no danger of his going overboard.

I claim:

1. An air and water craft having a forward propeller, and a float having a portion extending beneath the propeller, said portion affording an enclosed passageway past the propeller and provided with a hatch forward of the propeller, said hatch having a cover arranged to serve when raised as a shield to guard persons entering and leaving the hatch from the propeller.

2. An air and water craft having a forward propeller, a float having a portion extending beneath the propeller, said portion affording an enclosed passageway past the propeller and provided with a hatch forward of the propeller, said hatch having a cover arranged to serve when raised as a shield to guard persons entering and leaving the hatch from the propeller, and a toggle mechanism comprising members pivotally connected with each other and pivotally connected, respectively, with the float and with the hatch cover and constructed to lock the cover in its propeller-guarding position.

3. An air and water craft having a forward propeller, a float having a portion extending beneath the propeller, said portion affording an enclosed passageway past the propeller and provided with a hatch forward of the propeller, said hatch having a cover arranged to serve when raised as a shield to guard persons entering and leaving the hatch from the propeller, and a toggle mechanism comprising members pivotally connected with each other and pivotally connected, respectively, with the float and with the hatch cover and constructed to lock the cover in its propeller-guarding position and also in its closed position.
